UNITED STATES PATENT OFFICE.

BERNARD T. LEVEQUE, OF BOSTON, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-SEWING MACHINE.

1,019,667.

Specification of Letters Patent. Patented Mar. 5, 1912.

Application filed May 11, 1911. Serial No. 626,456.

To all whom it may concern:

Be it known that I, BERNARD T. LEVEQUE, a subject of the King of Great Britain, residing at Boston, county of Suffolk, State of Massachusetts, have invented an Improvement in Buttonhole-Sewing Machines, of which the following description, in connection with the accompanying drawing, is a specification, like characters on the drawing 10 representing like parts.

This invention relates to buttonhole sewing machines of the type known to the trade as the "Reece" machine wherein a stitch frame carrying stitch-forming mechanism 15 and a work-supporting or clamping frame are movable one with relation to the other to enable the stitching to be carried on along the sides of the buttonhole and about its enlarged end or eye. As illustrating some 20 sewing machines of this class, I would refer to United States Patents No. 494,280, dated March 28, 1893, No. 635,637, dated August 7, 1900, and No. 695,039, dated March 11, 1902, and No. 498,216, May 23, 1893.

25 In sewing machines of this type the stitch frame sustains an eye-pointed needle carrying the upper thread, and a complementary stitch-forming mechanism located below the stitch frame controls and operates an under 30 thread that is concatenated with the upper thread in the formation of the stitch.

One of the objects of my invention is to provide an improved complementary stitch-forming mechanism which is simplified in 35 its construction over that shown in said prior patents and which has an improved mechanism for operating the looper, and another object of the invention is to provide a novel form of take-up for the upper thread 40 which cooperates with the complementary stitch-forming mechanism in the formation of the stitch.

Referring now to the drawings wherein I have illustrated the preferred embodiment 45 of my invention, Figure 1 is a side view of the front portion of a sewing machine embodying the invention with a part of the frame broken out on the line $y-y$, Fig. 2, to show the complementary stitch-forming mechanism in elevation; Fig. 2 is a front view of Fig. 1 with part of the frame broken out; Figs. 3, 4 and 5 are different views of the stitch block and its associated parts forming the complementary stitch-forming mechanism; Fig. 6 is an enlarged sectional view

on substantially the line $x-x$, Fig. 4; Fig. 7 is a top plan view of the stitch block shown in Fig. 4; Fig. 8 is a side view of the looper carrier; Fig. 9 is a side view of the cam member for actuating the looper; Fig. 10 is a view of a detached part of said cam mechanism. Fig. 11 is a section on the line $b-b$, Fig. 1; Fig. 12 is a section on the line $a-a$, Fig. 1.

1 designates the main frame of the sewing machine, 2 the clamp frame, 3 a portion of the stitch frame which is movably mounted on the machine and which carries at its front end the needle bar 4 carrying the eye-pointed needle 5 which controls the upper thread 6. The stitch frame has associated therewith the bearings 7 and 8 in which the complementary stitch-forming mechanism is mounted, said complementary stitch-forming mechanism comprising a stitch block 9 rotatably mounted in the bearings 7 and 8 and supporting an under thread carrier in the form of a needle 51 which is secured to a needle carrier 50 that oscillates in a curved groove formed in the portion 49 of the stitch block. The stitch block 9 is provided with the usual gear 45 which meshes with the segmental rack 100 and by which the requisite oscillatory movement is given to said block. 75

59 is the actuating shaft which extends 80 axially through the sleeve 10 of the stitch block and by which the looper and under thread carrier 50 are operated, said shaft being given its vertical reciprocating movement by means of the lever 11 pivoted at 12. 90 The parts thus far described are or may be all as shown in said Patent No. 695,039 to which reference may be had, and as they form no part of the present invention I have not deemed it necessary to further describe 95 them herein.

In the way of simplifying the complementary stitch-forming mechanism I have made some improvements in the means for actuating the needle carrier 50. As herein 100 shown the shaft 59 has clamped thereto a sleeve 13 which is provided with a projecting stud 14 to which is fastened one end of a link 15, the other end of said link being pivotally connected at 18 to an elbow-lever 16 105 that in turn is pivoted to the block 9 at 17. Said elbow-lever extends up through the annular portion 20 of the block and at its upper end it has pivotal connection with a link 21 which is connected to the stud 22 110

extending from the needle carrier 50 and playing in a slot in the part 49. The vertical movement of the shaft 59 will through the mechanism above described operate the under thread carrier 50, as will be obvious, and this construction provides a simple but effective mechanism for securing this end.

Since the sleeve 13 is clamped to the shaft 59 it is possible to adjust said sleeve vertically on the shaft. The advantage of this construction is that this adjustment of the sleeve provides means whereby the position of the needle 51 can be adjusted relative to the position of the shaft 59 and without disturbing or altering the position of the looper or other parts of the sewing machine. It is sometimes desirable to be able thus to adjust the position of the needle and the mechanism herein shown permits this to be done.

20 The looper of the complementary stitch mechanism is shown at 63 and it is sustained by a looper carrier which is pivotally mounted at 64 on the portion 49 of the block and which is given its operation by 25 the vertical movements of the shaft 59 as described in said Patent No. 695,039. The motion which it is necessary to give to the looper is a compound one, that is, the looper is required to move transversely of the path 30 of the needle 51 in two different directions. One feature of my invention relates to the construction by which the looper is given its required movement and which will now be described. The looper carrier by which 35 the looper is sustained comprises the part 24 which is pivoted on the stud 64 that is sustained in the part 49 of the stitch block and the looper holder 25 to which the looper is directly connected and which is swiveled 40 to the part 24. As herein shown the looper holder 25 is provided with a stem 26 which is loosely received in a recess 27 formed in one arm of the member 24, said stem 26 extending at right angles to the stud 64 so 45 that the looper holder may have a turning movement in the part 24 about an axis at right angles to said stud 64. The part 24 is provided with the cam slot 28 in which is received a stud 490 carried by the upper end 50 of the shaft 59, all as shown in said Patent No. 695,039 whereby the vertical movement of the shaft 59 will oscillate the looper carrier about the stud 64. In order to effect the turning movement of the looper holder 55 25 relative to the part 24 I have provided a cam member 29 provided with a hub 30 which encircles and can turn about the sleeve or boss 31 formed on the part 24, as clearly seen in Fig. 6. This cam member 29 is also provided with a cam slot 32 in which the stud 490 is received, and said member has associated therewith a part 34 provided with an aperture 35 adapted to 60 embrace the rounded head 36 of a stud 37 that extends laterally from the looper

holder 25. The part 34 may be either integral with the cam member 29 or may be made as a separate part adjustably secured thereto. The latter is the construction shown in the drawings and the part 34 is shown as having the slot 38 through which is entered a stud screw 39 that screws into the arm 33 of the cam member 29, this providing for a fine adjustment of the aperture 35.

70 From the above it will be readily seen that if the cam member 29 is turned relative to the looper carrier, such relative movement will cause a slight turning of the looper holder 25 on its stem 26 due to the action of the part 34 on the head of the stud 37. The head of the stud is rounded as shown in Fig. 6 so that the parts will not be cramped by any such action.

75 The cam slot 32 is of a different shape from the cam slot 28, so that when the shaft 59 is raised the projection 490 will act first on the cam member 29 thereby rocking the latter relative to the looper carrier 24 with the result that the looper holder 25 is turned 80 on the part 24 to give the looper a movement to the left Fig. 3 and thereafter the stud 490 acts on the looper carrier to turn the latter about the stud 64 thereby to cause the looper to move toward the right from 85 the position shown in Fig. 4.

90 The difference in the outline of the cam grooves 32 and 28 will be clearly seen from an inspection of Figs. 8 and 9. In Fig. 8, for instance, the cam groove 28 has the relatively long straight side or dwell 40 which merges into the rise 41 that is situated at the center or upper portion of the cam, said rise in turn merging into a straight portion or dwell 84. On the other hand, the cam groove 32 has the relatively short straight portion or swell 42 at the lower end, a rise 43 which is situated near the lower end of the groove, and a longer straight portion or dwell 83 at the top. As a result when the shaft 59 is elevated the stud 490 will engage the rise 43 of the cam groove 32 while said stud is still moving over the straight portion or dwell 40 of the cam groove 28, thereby to 95 cause the cam member 29 to turn relative to the member 24, such turning movement rocking the looper holder 25 thereby to move the looper to the left Fig. 3, and as the stud 490 continues its upward movement it will 100 engage the rise 41 of cam groove 28, thus swinging the looper to the right Fig. 4, and as the stud enters the straight portion 83 of the cam groove 32 the parts 29 and 24 will 105 have a movement relative to each other 110 which will cause the looper to move to the right Fig. 3.

115 The shapes of the cam grooves 28 and 32 relative to each other are such that as the stud 490 moves up and down the looper 120 holder 25 and the looper 63 will be given the 125

requisite compound movement to cause it to engage the loop of needle thread, and then to draw said loop to one side or expand it and put said loop into position to be entered 5 by the under needle 51, and then to shed the loop, all as necessary in carrying out the stitching operation, and as will be clear to those skilled in the art. This mechanism is comparatively simple and can be operated 10 with great rapidity and has the further advantage that the looper is at all times moved positively in all directions and does not depend for any of its movements on a spring.

15 Another improvement which I have embodied in the complementary stitch-forming mechanism relates to the take-up for the under thread 44. Said thread passes up through the shaft 59, as described in said 20 Patent No. 695,039, and thence passes out through an elongated opening or slot 46 formed in said shaft, thence through a guide eye 47 carried on the end of an arm 48 that is secured to the stitch block 9, thence 25 through a tension device 53 of any suitable construction, thence up inside of the ring-shaped portion 20 to the thread guide 81 carried by the needle carrier 50, and thence to the under needle 51. The parts are so 30 disposed that in the operation of the machine when the needle carrier 50 moves forwardly to carry the under needle 51 up through the slit in the work the thread required for this forward movement of the 35 under needle is furnished by the slack in the bight 54 that is given up by the forward movement of the thread guide 81, and when the under needle 51 reaches the limit of its movement the thread will be drawn taut.

40 When the needle carrier begins its backward movement the thread will at first be somewhat slack, but when the needle carrier has been retracted to such a point that the thread guide 81 is carried to the right of 45 the portion of the ring 20 with which the thread contacts, then the further backward movement of the thread guide forms a bight 54 in the thread, and in forming this bight the thread is taken up sufficiently to tighten 50 or set the stitch and to draw on the supply end of the thread through the tension 53. I propose to use a fairly heavy tension 53. With my improvements, therefore, the stitch is set by the backward movement of the 55 needle carrier 50 co-acting with the tension 53 and without the necessity of a take-up or other moving part, such as employed in Patent No. 695,039. The omission of the take-up simplifies very much and reduces 60 greatly the number of parts of this complementary stitch-forming mechanism.

In the machine shown in said prior patents the upper thread 6 which is controlled by the eye-pointed needle 5 passes over a 65 movable take-up shown at 96 in Patent No.

498,216, May 23, 1893, such take-up being operated by means of suitable cam mechanism for taking up the slack in the upper thread 6 at the proper time to effect the setting of the stitch. In my improvement I 70 have done away with this movable take-up and instead employ a stationary take-up which co-operates with the needle bar 4 to effect the taking up of the slack of the thread and the setting of the stitch. As 75 herein shown, my improved stationary take-up comprises a guide eye 70 carried by a finger 71 that is connected to the stitch frame 3 in any suitable way, as by means of a clamping screw 72. This take-up is of 80 such a shape that the eye 70 thereof comes substantially on a level with the top of the needle bar 4 when said bar is in its elevated position and said take-up is situated between said needle bar and the tension 85 73. As the needle bar 5 descends the thread 6 is supported by the eye 70 which thus takes up the slack in the thread that would be caused by the downward movement of the needle bar, said thread occupying the dotted 90 line position Fig. 1 when the needle bar is in its lowered position. As the needle bar is elevated it acts on the thread to set the stitch and to draw off a fresh supply. I 95 find that with this stationary take-up the slack in the needle thread caused by the sewing operation is taken care of sufficiently so as to obviate any snarling, tangling, or breaking of the thread, and at the same time to set the stitch firmly. The substitution 100 of this fixed take-up for the movable take-up and the cam mechanism shown in said Patent No. 498,216 simplifies the construction of the machine very much and reduces 105 materially the number of parts.

The studs 14 and 18 are provided with ball-shaped ends and the link 15 is provided at its ends with sockets to receive the ball, thus making a flexible connection between the shaft 59 and the elbow lever 16. Similarly the stud 22 is provided with a ball end which is embraced by a socket 88 carried on the link 21. It will be noted that the lever 16 stands at a slight inclination so as to operate in a plane approximately parallel to that in which the needle carrier 50 operates. The ball-and-socket joint 88, however, permits the parts to operate freely even though the lever 16 is not in absolute alignment. Further, the ball-and-socket joints 110 between the link 15 and the studs 14 and 18 permit the lever 16 to be operated without any binding or cramping.

Having fully described my invention, what I claim as new and desire to secure by 125 Letters Patent is:—

1. In a buttonhole sewing machine, the combination with a needle for controlling the upper thread and means for operating it, of supplemental under thread-carrying 130

- mechanism comprising an oscillatory block, a needle for the under thread sustained by said block, a shaft extending axially of the block, means to give the shaft a longitudinal movement, means to operate the needle for the under thread by movement of the shaft, a looper also sustained by said block, and connections between said shaft and looper by which the latter is operated and its position is controlled positively at all times by the shaft.
2. In a buttonhole sewing machine, the combination with a needle for controlling the upper thread and means for operating it, of complementary under thread-carrying mechanism comprising an oscillatory block, a needle for the under thread sustained by said block, a looper also sustained by said block, and two cams movably sustained by said block, one operating to control positively at all times the movement of the looper in one direction and the other operating to control positively at all times the movement of the looper in another direction.
3. In a buttonhole sewing machine, the combination with a needle for controlling the upper thread and means for operating it, of complementary under thread-carrying mechanism comprising an oscillatory block, a needle for the under thread sustained by said block, a looper carrier pivoted to the block and provided with a cam groove, a looper holder swiveled to said carrier, a looper sustained by the holder, a cam member connected to the looper holder, and a reciprocating stud operating in said cam groove and also operating said cam member thereby to give the looper its desired movement.
4. In a buttonhole sewing machine, the combination with a needle for controlling the upper thread, of a complementary under thread-carrying mechanism including an oscillatory block, a needle for the under thread, an oscillating looper carrier, a looper holder pivoted to the looper carrier and provided with a laterally-extending stud, a looper sustained by said holder, a cam member connected to said stud and mounted to turn about the axis of movement of the looper carrier, and means for operating the cam member thereby to oscillate the looper holder in the looper carrier.
5. In a buttonhole sewing machine, the combination with a needle for controlling the upper thread, of a complementary under thread-carrying mechanism including an oscillatory block, a needle for the under thread, an oscillating looper carrier, a looper holder pivoted to the looper carrier and provided with a laterally-extending stud, a looper sustained by said holder, a cam member connected to said stud and pivotally mounted to move about the axis of the
- looper carrier, and a shaft reciprocating in said block and provided with a stud engaging the cam member.
6. In a buttonhole sewing machine, the combination with a needle for controlling the upper thread, of a complementary under thread-carrying mechanism including an oscillatory block, a needle for the under thread, a looper carrier pivoted to said block and provided with a cam groove, a looper holder swiveled to the looper carrier and provided with a laterally-extending stud, a looper carried by said holder, a cam member pivoted on the looper carrier and engaging said stud and also provided with a cam groove, and a reciprocating member having a stud operating in both of said grooves whereby movement of the stud will oscillate the cam member relative to the looper carrier and also oscillate the looper carrier thereby to give the looper its required compound movement.
7. In a buttonhole sewing machine, the combination with an oscillatory block, of a reciprocating needle carried thereby, a looper carrier pivoted thereto and having a cam groove, a looper holder swiveled to the looper carrier and provided with a laterally-extending stud, a looper sustained by said holder, a cam member pivoted on the looper carrier to turn about the axis thereof, a member 34 adjustably connected to the cam member and embracing said stud, and a shaft reciprocating in said block and provided with a stud acting on said cam member and in the cam groove of the looper carrier thereby to give the proper movement to the looper.
8. In a buttonhole sewing machine, the combination with a needle for controlling the upper thread, of a complementary under thread carrier mechanism including an oscillatory block, a needle for the under thread, an oscillating looper carrier, a looper holder pivoted to the looper carrier to turn about an axis substantially at right angles to that of the looper carrier, said looper holder having a stud extending laterally parallel to the axis of the looper carrier, a looper sustained by said holder, a controlling member turning about the axis of movement of the looper carrier and connected to said stud, and means for operating said controlling member thereby to move the looper relative to the looper carrier.
9. In a buttonhole sewing machine, the combination with a needle for controlling the upper thread, of a complementary under thread-carrying mechanism comprising an oscillatory block, a needle carrier oscillating therein and provided with a stud, an elbow lever pivoted to the block and connected to said stud, a shaft 59 reciprocating in said block, a sleeve clamped to said shaft and having a laterally-extended stud with a ball

end, a ball-ended stud extending from the elbow of said lever, and a link connecting the two ball-ended studs, said link having at each end a socket to receive said balls.

- 5 10. In a buttonhole sewing machine, the combination with a needle for controlling the upper thread, of a complemental under thread-carrying mechanism comprising an oscillatory block, a shaft reciprocating in said block, a looper operated by said shaft, a needle carrier oscillating in said block and provided with a stud, an elbow lever pivoted to the block and connected to the stud, and an adjustable connection between said shaft 15 and said lever and including a link pivotally connected to each and by which longitudinal movement of the shaft oscillates the lever, the adjustability of said connection permitting said lever and the needle to be adjusted 20 relative to the shaft and looper mechanism.
11. In a buttonhole sewing machine, the combination with a needle for controlling the upper thread, of a complemental under thread-carrying mechanism comprising an 25 oscillatory block, a shaft reciprocating in said block, a looper operated by said shaft, a needle carrier oscillating in said block and provided with a stud, an elbow lever pivoted

to the block and connected to said stud, a sleeve adjustably connected to said shaft and 30 having a laterally-extending stud, a stud extending from said elbow lever, and a link connecting said two latter studs, the adjustability of the sleeve on the shaft providing for adjustment of the needle relative to the 35 looper.

12. In a buttonhole sewing machine, the combination with a needle for controlling the upper thread, of a complemental under 40 thread carrier mechanism comprising an oscillatory block, a needle carrier oscillating therein, an elbow lever pivoted to the block and connected to said carrier, a shaft reciprocating in the block, and adjustable connections between said shaft and lever, said 45 connections including a sleeve clamped to the shaft, and a link connecting said sleeve with the lever.

In testimony whereof, I have signed my name to this specification, in the presence of 50 two subscribing witnesses.

BERNARD T. LEVEQUE.
